DESIGN FOR A GLASS BOTTLE

George W. Aiken, Mount Lebanon Township,
Allegheny County, Pa., assignor to J. T. & A.
Hamilton Company, Pittsburgh, Pa., a corporation of Pennsylvania

Application March 19, 1942, Serial No. 106,255

Term of patent 3½ years

To whom it may concern:

Be it known that I, George W. Aiken, a citizen of the United States, residing at Mount Lebanon Township, in the county of Allegheny and State of Pennsylvania, have invented a new, original, and ornamental Design for a Glass Bottle, of which the following is a specification, reference being had to the accompanying drawing forming part thereof.

In the drawing Fig. I is a view of a glass bottle in plan from above, showing my new design; and Fig. II is a view of the bottle in front elevation.

The back of the bottle is identical with the front.

I claim:

The ornamental design for a glass bottle, substantially as shown and described.

GEORGE W. AIKEN.
